UNITED STATES PATENT OFFICE.

HARRY MINTZ, OF BOSTON, MASSACHUSETTS.

HAMMOCK.

1,414,433.

Specification of Letters Patent.

Patented May 2, 1922.

Application filed July 19, 1921. Serial No. 485,860.

To all whom it may concern:

Be it known that I, HARRY MINTZ, a citizen of the United States of America, and resident of Boston, in the county of Suffolk and State of Massachusetts, have invented 5 new and useful Improvements in Hammocks, of which the following is a specification.

This invention relates to hammocks and 10 is a continuation in part of an application filed by me on April 23, 1921, Ser. No. 463,897. More particularly the invention relates to that type of hammock commonly called "cotch" or "Gloucester" hammocks 15 comprising essentially a rigid spring-carrying seat frame adapted to support a mattress or cushion, end and back members of canvas or other suitable textile material and flexible suspension or supporting members.

20 Hammocks of this type which, as is well known, were originally adapted and intended for use merely as porch swings, have now come to be regarded as indispensable articles of furniture in many situations such as upon carefully furnished protected verandas or in closed rooms such as sun porches or the like where an out-of-doors atmosphere or environment is desired. To meet these conditions of service it is essential 25 that the hammock shall not only provide a very comfortable seat but shall be of such construction as to permit it to be made of materials which will harmonize in texture and colors with the environment in which it 30 is hung, and which has customarily been carefully planned, often at large expense, to produce an artistic effect of which the furnishings form an essential element.

35 It is the object of this invention to provide a hammock primarily intended for use 40 under these conditions of service and to that end so constructed as to permit the fabric portions thereof to be made of any material desired by the user, or which the particular environment may require, at the same 45 time embodying means which are both conducive to the comfort of the user and adapted to enhance the decorative effect and general visual appearance of the device.

50 Referring to the drawings which illustrate certain embodiments of the invention,—

Figure 1 is an end elevation of a hammock embodying the invention;

55 Figure 2 is a section on the line 2—2 of Fig. 1, but to larger scale;

Figure 3 is a view similar to Fig. 1 showing a modified form; and

Figure 4 is a section on the line 4—4 of Fig. 3, but to larger scale.

Referring to Figs. 1 and 2, 1 is a mattress supporting frame of usual construction comprising side and end rails, the latter being preferably made of angle iron as clearly shown in Fig. 2.

Said frame is adapted to support a mattress or cushion 2. Extending upwardly from the frame there is provided a back rest 3 which may be of any usual construction, but which is preferably of the form shown secured to the frame by means of links 4 secured to brackets 5 carried by the side rails of the frame. The exact arrangement and mode of connection of the back rest is not, however, a part of the present invention.

8 indicates one of a pair of flexible supporting members such as chains which may depend from any suitable elevated support. At their lower ends these supporting members are preferably provided with rings 7, to which are secured chains such as 6, the opposite ends of which are connected to the back rest 3 to hold the latter in adjusted position. From the rings 7 also depend pairs 80 of suspension members such as the chains 9, the lower ends of said chains being secured to the end bars of the seat frame in any suitable manner, as by bolts 10, so that the seat frame is thus directly supported by the suspension devices. Preferably the chains 9 are provided below the upper edge of the back rest 3 with suitable means such as the S-links S, constituting stops for a purpose 85 hereinafter described.

90 At each end of the hammock there is provided a rigid bar or rail 15 constituting an arm rest, such bar being provided with vertical openings 16 adjacent its extremities. Preferably such openings are spaced inwardly from the extremities of the bar and are of a diameter to permit the free passage of the chain therethrough. As shown in Figs. 1 and 2, the upper surface of the bar 15 between the apertures 16 is downwardly concave so as to conform more or less closely to the shape of the arm of the user, but it will be understood that the particular shape or contour is not essential.

95 At a suitable point above the mattress 2 there is provided a bar 11, secured adjacent its opposite ends to the chains 9 in any suit-

able manner, as by bolts. Said bar 11 is inserted within a fold or pocket provided at the top end of the fabric end member or screen 12. Said end member or screen extends downwardly inside the plane of the chains 9 to the plane of the frame where it is provided with a pocket in which is inserted a bar 13 (Fig. 2) having openings for the reception of the bolts 10 by means of which the chains 9 are attached to the end rail of the seat frame. Preferably said end member extends downwardly to form a valance 14 which serves to conceal the frame and to enhance the visual appearance of the hammock. The arm rest 15 is normally seated upon the bar 11 and is adjustable to varying heights within the limits defined by said bar 11 and the S-links or stops S.

The hammock shown in Figs. 3 and 4 is of the same construction as that just described, except that the arm rest 15^a instead of being flat upon its under surface is downwardly curved throughout its central portion and provided with a groove 17 (Fig. 4) adapted to receive the bar 11 so that said arm rest 15^a may be normally seated upon said bar 11.

While in general the device has been disclosed and described as applied to one end only of a hammock, it should be understood that the same structure is employed at both ends although if desired the end member and arm rest may be omitted or removed from one end of the hammock with reference to the presence of such device at the other end.

It is believed from the foregoing description it will be clear that as the entire weight of the hammock and its occupants is carried by the supporting chains 9, the fabric ends of the hammock are not subjected to these strains or stresses which are present in hammocks wherein the fabric ends are utilized as supports for the seat frame necessitating the use of canvas or other very strong material of which the range of texture and colors is very limited. Consequently, in hammocks constructed in accordance with my invention any desired fabric may be employed, with the result that any desired artistic effect which is dependent upon the texture of materials or their colors, may be obtained. It will also be clear that as the arm rest is independent of the other elements of the end members it can not only be adjusted to varying heights but can be made of the form or contour best adapted to enhance the artistic effect of the hammock. It also results from the fact that the arm rest is an independent member, that it need not be covered with the same material employed in the making of the other elements of the hammock, but may if desired be of different or contrasted material or color and cushioned or otherwise especially adapted to unique and special situations.

While I have shown two forms of arm rests to illustrate the use of straight and curved lines, it will be understood that these forms are illustrative only, and that other forms may be employed without departing from my invention.

I claim:

1. A hammock comprising a seat frame, flexible supports engaging and directly supporting said frame, a vertically adjustable arm rest having openings adjacent to its ends, said supports passing freely through said openings and means independent of said arm rest for supporting a strip of fabric constituting a wind shield.

2. A hammock comprising a seat frame, flexible supports engaging and directly supporting said frame, a vertically adjustable arm rest having openings adjacent to its ends, said supports passing freely through said openings, stop means carried by said supports above and below said arm rest to limit the movement thereof on said supports, and a strip of fabric constituting a wind shield supported by the lower of said stop means.

3. A hammock comprising a seat frame, flexible supports engaging and directly supporting said frame, an end member comprising a bar carried by said supports and adapted to support a strip of fabric, and an arm rest mounted upon said supports above said bar.

4. A hammock comprising a seat frame, flexible supports engaging and directly supporting said frame, an end member comprising a bar carried by said supports, and an arm rest, engaging said supports above said bar, said arm rest having a curved arm supporting surface intermediate its ends.

5. A hammock comprising a seat frame, flexible supports engaging and directly supporting said frame, an end member comprising a bar carried by said supports and adapted to support a strip of fabric, and an arm rest having a downwardly curved portion mounted upon said supports, said arm rest having a groove in its under side adapted to receive said bar whereby said arm rest may be normally seated on said bar.

6. A hammock comprising a seat frame, flexible supports engaging and directly supporting said frame, an end member comprising a bar fast on said supports, and a strip of fabric secured to said bar at its top and to said seat frame at its bottom, and an arm rest mounted upon said supports above said bar.

7. A hammock comprising a seat frame, flexible supports engaging and directly supporting said frame, an end member comprising a bar fast on said supports, a strip of fabric secured to said bar at its top and to said seat frame at its bottom, and an arm rest having a downwardly curved portion

mounted upon said supports above said bar and having a groove in its under side adapted to receive said bar whereby said arm rest may be normally seated on said bar.

- 5 8. A hammock comprising a seat frame, flexible supports engaging and directly supporting said frame, an end member comprising a pair of bars, one secured to said supports and the other to said seat frame, a
10 strip of fabric stretched between said bars, and an arm rest mounted on said support and adapted normally to seat upon the

bar to which the top of said fabric strip is secured.

9. A hammock comprising a seat frame, 15 flexible supports engaging and directly supporting said frame, an end member comprising a fixed element and a movable arm rest element, said movable element being disposed above said fixed element and adjustable to varying heights upon said supports. 20

Signed by me at Boston, Massachusetts,
this 18th day of July, 1921.

HARRY MINTZ.
